(57) **CLAIM**

The ornamental design for a suture instrument, as shown and described.

DESCRIPTION

FIG. 1 is a front left side isometric view of a suture instrument in accordance with the new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken away symbols in the drawings indicate that any portion of the article beyond what is shown forms no part of the claimed design.

1 Claim, 6 Drawing Sheets

FIG. 5

FIG. 6

FIG. 7
